UNITED STATES PATENT OFFICE.

ALBERT E. F. GILSON, OF ORADELL, NEW JERSEY, ASSIGNOR TO WESTERN ELECTRIC COMPANY, INCORPORATED, OF NEW YORK, N. Y., A CORPORATION OF NEW YORK.

SIGNALING SYSTEM AND APPARATUS.

Application filed May 28, 1923. Serial No. 641,809.

This invention relates to signaling systems and apparatus, and more particularly to a unitary structure of a loud speaking receiver and amplifier set.

5 An object of the invention is the arrangement of a loud speaker horn and an electron discharge amplifier set in a compact form.

The invention, according to its preferred embodiment, provides compactly arranged 10 in a cabinet yet easily accessible, a loud speaker horn, at the rear of which and forming a part of the cabinet, is located a panel carrying amplifier apparatus which is arranged to occupy the space on either side 15 of the horn. In order to facilitate the control of the apparatus, suitable control devices are arranged on the front of the cabinet.

A better understanding of the invention 20 may be had from the following description, taken in conjunction with the accompanying drawings wherein Fig. 1 is a front elevation of the cabinet. Fig. 2 is a rear elevation of the cabinet. Fig. 3 shows the rear 25 interior of the cabinet. Fig. 4 is a horizontal sectional view. Fig. 5 shows the interior of the cabinet with the panel removed, while Fig. 6 shows diagrammatically the circuit arrangement of the various parts of the apparatus.

Referring now to the drawings, there is shown a wooden cabinet 4 having in the front thereof a lattice work 5, on the back of which is secured a netting 6 for preventing 35 the entrance of foreign substances into the interior of the cabinet. Hinged to the rear of the cabinet are a pair of doors 7-7, each having apertures 8, the purpose of which will be more clearly described herein- 40 after.

Arranged on the inside of the cabinet 4 is a folded wooden horn 10 in which the progressive increase in cross-sectional area follows the exponential law. Specifically, 45 this feature contemplates a horn tapered such that the areas of successive wave fronts increase by a constant per cent per unit of length. The characteristics of such a horn are clearly set forth in a copending application to H. C. Harrison, Serial No. 628,168, 50 filed March 28, 1923, and since the horn structure per se does not form a part of the present invention, a detailed description thereof is believed unnecessary.

55 Mounted at the rear of the horn 10 and

within the cabinet 4 is a panel 12 which is secured by means of suitable screws to uprights 13 and 14 mounted on each side of the cabinet, and carries the apparatus comprising the amplifier set.

60 Referring now for the moment to Fig. 6, a multi-stage amplifier circuit is disclosed comprising a vacuum tube repeater 17 constituting the first stage of amplification and two vacuum tubes 20 and 21 forming the 65 second stage of amplification. Each of the tubes 17, 20 and 21 is illustrated as the three-element tube electron discharge device. Each comprises an anode, a cathode and a control electrode. The input electrodes of 70 the tube 17 are connected to the incoming line 16 by a transformer 22 having a primary and secondary winding, in the latter, there being connected a switch 23 for controlling the degree of transformation for the 75 output of the transformer 22 and consequently the output of the amplifier set. The output electrodes of the tube 17 are connected by means of an intermediate transformer 24 to the input electrodes of the 80 tubes 20 and 21, while transformer 25 serves as a coupling means between the output circuits of these tubes and the leads 26. Space current for the vacuum tubes is supplied from a battery 28 connected between the 85 cathode and anode electrodes of the respective tubes. The desired static potential for the control or grid electrodes of the tubes supplied from a battery 27 which is connected between the filament and control 90 electrodes. Currents for lighting the filaments may be supplied by a battery 38 through terminals 29 located on the panel 12 and a filament switch 30.

95 As shown in Figs. 4 and 5, the shape of the horn 10 is such as to form triangular-shaped spaces on either side in which the apparatus constituting the amplifier 7 is located excepting those parts which necessarily require replacement from time to time. In 100 accordance with the showing of Figs. 3 and 4, the transformers 22, 24 and 25 are mounted on the front of the panel 12 (looking from the front of the cabinet) as well as the sockets 31 for the various vacuum tubes, the tubular portions of which fit in apertures in the panel 12, and occupy the space on either 105 side of the horn 10. The vacuum tubes thus project to the rear of the panel and consequently may be readily removed without dis- 110

turbing the position of the panel. Also mounted on the back of the panel 12 are batteries 27 and the switch 23, the latter cooperating with a series of contacts arranged on the arc of a circle for varying the output of transformer 22. The batteries 27 rest on a phenol fiber strip 32 secured to panel 12 and held in position by means of a strap 33. Each of the batteries 27 is provided with 10 spring contact terminals arranged to be fastened to suitable terminal clips 34.

In the bottom of the cabinet below the terminal posts is an aperture through which the incoming connections pass.

15 In the panel 12 and in alignment with the throat of the horn 10 is an aperture 35 through which projects a portion of a loud speaking receiver 36 also carried by the panel 12 and having its terminals connected to the leads 26 (Fig. 6). The loud speaking receiver 36 is thus directly coupled to the horn 10 and translates the electrical vibrations received by the amplifying apparatus into audible tones.

25 Only two elements of the combination require mechanism for controlling their operation, these being the output switch 23 and the filament switch 30. To permit the easy control of these elements, each switch is provided with a rod 37 extending from the associated switch through apertures in the sides of the horn, and the lattice work 5 to the front of the cabinet. Each of these rods has one end bifurcated for engaging pins individual to each of the switches thereby making it possible to remove the panel and still afford a simple and quick method of attaching the rods to their associated switch. To the other end of the rods, there is secured 30 a suitable knob for permitting the rotation of the rods and the operation of the switches. Associated with each of the knobs is a circular designating plate descriptive of the particular function of the switch.

45 In order to facilitate the location of the rods 37 with their associated switch, the bottom 39 of the cabinet is made removable. The rods may thus be guided so that the pin 50 in the switch fits in the bifurcated portion of the rod.

As the amplifier set is oftentimes operated for long periods of time, experience has found that the vacuum tubes produce excessive heating. To avoid damage to the cabinet and apparatus therein which may be caused by the heat generated by the vacuum tubes, each of the doors 7-7 is provided with apertures 8 to permit the free circulation of the air to and from the vacuum tube 55 compartment. These apertures in addition to acting as ventilators also serve as a means for enabling the detection as to whether the filaments of the vacuum tubes are lighted.

From the previous description it is appar-

ent that such a structure readily lends itself 65 to its use with panels carrying various types of apparatus, due to the fact that the panels are interchangeable.

What is claimed is:

1. In combination, a cabinet, a folded 70 horn disposed in said cabinet in a manner to form triangular spaces adjacent the opposite sides of the small end of said horn, a removable partition in said cabinet adjacent the small end of said horn, electrical operating means for said horn carried by said partition and arranged in said triangular spaces, a receiver on said partition supporting the small end of said horn, means manually operable for controlling the output of said operating means, said controlling means extending through said spaces from the front of the cabinet, and loose coupling means carried by the operating and controlling means 75 for permitting the removal of said partition and electrical operating means from said cabinet as a unit without obstruction from said controlling means.

2. In combination, a cabinet, a horn 80 mounted in said cabinet in a manner to form triangular spaces on two sides thereof, a removable partition in said cabinet, electrical operating means for said horn mounted on said partition and projecting into said triangular spaces, a receiver on said partition supporting the small end of said horn, controlling means for said operating means comprising rods extending through said triangular spaces in line substantially parallel to opposite sides of said cabinet, and loose coupling means carried by said rods and said operating means for permitting the removal and mounting of the partition in the cabinet as a unit.

3. In combination, a cabinet, a loud speaker horn mounted in said cabinet, a removable partition in said cabinet, a receiver secured on said partition engaging the small end portion of said horn by a slip-fit arrangement, amplifying devices carried by said partition and occupying the spaces bounded by the walls of the cabinet and the sides of the horn, said devices being operatively connected to said horn, switches carried by the partition for controlling the output of said devices, and a plurality of control means operable from the front end portion of said horn for actuating said switches, said control means including loose couplings cooperating with the slip-fit arrangement of the horn in 110 the receiver for permitting the mounting or removal of said partitions and receiver from the cabinet as a unit and without obstruction from said horn and the control means.

In witness whereof, I hereunto subscribe 115 my name this 25th day of May A. D., 1923.

ALBERT F. F. GILSON.
